Primary Examiner — Cynthia Ramirez(74) *Attorney, Agent, or Firm* — Fitch, Even, Tabin & Flannery LLP(57) **CLAIM**

I claim the ornamental design for a conveyor transfer guard, as shown and described.

DESCRIPTION

FIG. 1 is a perspective view of a conveyor transfer guard, showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines in the figures are included for the purpose of illustrating portions of the conveyor transfer guard and form no part of the claimed design.
